UNITED STATES PATENT OFFICE.

CHARLES W. SMITH, OF OAK PARK, ILLINOIS.

DESIGN FOR A CURTAIN-POLE BRACKET.

SPECIFICATION forming part of Design No. 25,272, dated March 24, 1896.

Application filed February 10, 1896. Serial No. 578,799. Term of patent 7 years.

To all whom it may concern:

Be it known that I, CHARLES W. SMITH, a citizen of the United States, residing at Oak Park, in the county of Cook and State of Illinois, have invented and produced a new and original Design for Curtain-Pole Brackets, of which the following, in connection with the accompanying drawings, is a full, clear, and exact specification.

10 In the said drawings, Figure 1 is a face view of a curtain-pole bracket embodying my design, and Fig. 2 is a side elevation thereof.

The leading features of my design consist of the portion A and the knob-like or bulbular portions B surrounding the same. The portion A is a spheroid, and it is surrounded by the smaller spheres or balls B. From the upper or outer side of the portion A projects an ornament C, whose inner end is formed on 15 outcurves c, while its outer end or point is formed on incurves c', which converge at

their outer ends, as shown in Fig. 2. On the lower or inner side of the portion A is formed another spheroidal portion D, which is slightly larger than A and in which is formed the recess or cavity E for the reception of the pole, such cavity being angular, as shown in full lines, or round, as shown in dotted lines, and the lower or inner side of the sphere D is rounded off into compound curves F, which 25 form a narrow waste, as shown in Fig. 2, and a broadened foot or base G.

Having thus described my invention, what I claim as new, and desire to secure by Letters Patent, is—

30 The design for curtain-pole brackets, substantially as herein shown and described.

CHARLES W. SMITH.
